UNITED STATES PATENT OFFICE

ERNEST ROBERT SWANSON, OF CRANSTON, RHODE ISLAND, ASSIGNOR TO UNIVERSAL WINDING COMPANY, OF BOSTON, MASSACHUSETTS, A CORPORATION OF MASSACHUSETTS

COP-HOLDER

Application filed July 9, 1928. Serial No. 291,420.

This invention relates to improvements in cop-holders or mandrels of the type used with winding machines and other textile apparatus.

5 The invention consists in general in providing a rotatable holder or mandrel for supporting a tube, core or other receiver on which yarn, thread or similar attenuated material is to be wound.

10 One object of the invention is to provide means for rotatably mounting the cop-holder on the winding machine or other textile apparatus whereby the cop will be maintained uniformly in contact with the drum by which 15 it is driven.

Another object of the invention is to provide means for mounting the cop-holder on the dead-spindle of a winding machine or other textile apparatus whereby it is carried 20 on anti-friction bearings to adapt it for high speed rotation without excessive wear of the parts.

Another object of the invention is to provide a cop-holder of simplified structure 25 which is economical to manufacture and of greater durability and efficiency in use.

Further objects of the improvement are set forth in the following specification which describes a preferred form of construction 30 of the invention as illustrated by the accompanying drawings. In the drawings:

Fig. 1 is a part sectional view showing the improved cop-holder mounted to rotate on a dead-spindle and carrying a conical cop or 35 package driven from a cylindrical drum or drive-roll; and

Fig. 2 is a longitudinal section of the cop-holder, taken on the line 2-2 of Fig. 1.

In the present application the improved 40 cop-holder is described as adapted for winding a conical cop on a paper core or support, but it is to be understood that the core may take other forms and be constructed of any suitable material.

45 In friction or drum-driven winding machines the cop or package is usually wound on a cop-holder which is rotatably mounted on a dead-spindle and adapted to be driven through surface contact of the winding with 50 a rotating drum or drive-roll. As herein

shown the dead-spindle 11 is swiveled at the end of an arm 12 and is normally held in inclined relation with respect to the periphery of the drive-roll 13. The arm 12 may be suitably arranged to adapt the cop-holder to 55 move away from the drive-roll as the package increases in size during the winding. The cop may also be wound in cylindrical form and various types of cores or holders are employed for supporting the 60 package at its center. In some cases paper or cardboard tubes are used for this purpose and in other instances wooden, composition or fiber cores or yarn-receivers are employed.

As herein illustrated the yarn-receiver 65 comprises a conical paper shell or tube T having a closed apex end and an open base or butt end into which the cop-holder is adapted to be inserted.

The main body of the spindle 11 is preferably constructed in shouldered form, its rear or inner portion 15 being larger in diameter than the outer portion 16 thereof with the shoulder 17 intervening therebetween. The 70 purpose of the shoulder 17 will be herein-after more fully explained. The smaller portion 16 of the spindle 11 terminates in a conical tip 18.

As herein illustrated the cop-holder for 75 mounting the tube or yarn-receiver T comprises an elongated cylindrical sleeve 19, the outer end of which is formed with a conical boss 20, while at its opposite end is a hub 21 supporting a conical cupped flange or boss 22. The peripheries of the bosses 20 and 22 80 are tapered to correspond substantially with the interior of the conical tube T.

The outer end of the sleeve 19 is formed 85 with an axially disposed opening 23 which is threaded for the reception of a hardened screw-plug 24. The inner end of the plug 24 is formed with a conical recess 25 which constitutes a bearing seat for the tip 18 of the spindle 11. The plug 24 is maintained 90 in fixed position in the opening 23 by means of a lock-nut 26 threaded onto the projecting portion of the plug and set up against the end of the boss 20. In this way the plug 24, 95 after being properly positioned in the end 100

of the sleeve 19, may be locked in its adjusted position.

The end of the hub 21 on the sleeve 19 is counter-bored to provide an annular recess 27 in which is disposed an annular ball-bearing comprising an interiorly grooved ring 28 cooperating with an exteriorly grooved ring 31 on the spindle 11. Between the rings 28 and 31 are a plurality of balls 33 which travel in the grooves or races of the bearing.

The portion 16 of the spindle 11 adjacent to the shoulder 17 is enlarged slightly at 29, and between this enlargement and the shoulder 17 there is an annular groove 30. This construction permits the bearing ring 31 to be slid along the portion 16 of the spindle 11 and forced on to the enlarged portion 29, so that the ring will be mounted fast on the spindle with its end face abutting the shoulder 17, as clearly shown in Fig. 2. Any other suitable means may be employed for fastening the bearing ring 31 to the spindle 11, such as by pin or set-screw, whereby the ring will be prevented from sliding longitudinally of the spindle.

Held in the counterbore 27 of the hub 21 on the sleeve 19 is a collar 32 which bears against the outer ring 28 of the bearing with a clearance around the enlarged portion 15 of the spindle 11. The collar 32 is retained in position by means of set-screws 34 extending through the hub 21 at the rear end of the sleeve 19.

The construction is such that the bearing constitutes means for taking both the lateral and end thrust of the sleeve 19 on the spindle, as well as permitting the sleeve to rotate freely at high speeds.

Due to this manner of mounting the sleeve 19 on the spindle 11, the tip 18 of the spindle need not be tightly seated in the recess 25 in the plug 24, the plug being adjustably positioned with respect to the end of the spindle 45 to center the outer end of the sleeve on the spindle to provide for free rotation of the sleeve without undue play or vibration.

In order that the bearings at each end of the spindle may be readily lubricated, the sleeve 19 is bored near its outer and inner ends at 37 and 38 respectively. A small amount of oil injected through the openings 37 and 38 maintains the bearings lubricated over long periods.

To prevent the free lubricant in the device from being thrown onto the material being wound, the spindle 11 carries a dish-shaped collar 40 at its rearward end. The collar 40 may have an outwardly extending inclined flange of a diameter slightly less than that of the cupped flange 22 on the end of the sleeve 19 and disposed with its rim projecting thereinto to substantially close the rear or open end thereof. It will be observed that any oil thrown rearwardly from the

bearings will be caught in the flange on the collar 40, and in this way damage to and waste of the yarn or thread in the package will be prevented.

For the purpose of detachably retaining the tube T on the cop-holder, a pair of spring-fingers 41 may be employed. These fingers 41 are diametrically opposed on the periphery of the device with one end fastened to the sleeve 19 by screws 42 or through other means. The free ends of the fingers 41 project towards the base or butt end of the tube T, passing through openings 45 in the vertical wall of the flanged portion 22 of the sleeve. As shown in Fig. 1, each of the fingers 41 is arched intermediate its length with its free end directed towards the spindle 11. The terminal portions of the fingers 41 are turned inwardly at 43 to engage under the rim of the flange on the collar 40. The fingers 41 are formed with outwardly projecting prongs 44 intermediate their ends which are adapted to bite into the interior of the tube to secure it in place on the holder.

Manually-operated means are usually provided for operating the collar 40 to release the holding means for the cop-tube or yarn-receiver. For this purpose the collar 40 may be slid forwardly on the spindle 11 to force the fingers 41 radially inward to withdraw the prongs 44 from the tube T whereby to permit removal or doffing of the completed cop from the holder.

It will be observed from the foregoing that the present invention provides a particularly simple, compact and efficient device for the purpose specified and one in which the parts are designed for economical manufacture. The method of mounting the cop-holder on the spindle 11 whereby the lateral and longitudinal thrust is taken by the ball-bearing is of considerable importance as providing that the holder will rotate freely without undue friction at the outer end bearing.

The improved arrangement of the bearings not only materially reduces the frictional resistance to high-speed rotation of the holder, but further and most important it greatly increases the durability of the whole device. As another advantage, the use of the present light-running bearings provides that the cone-holder may be easily rotated by a pull on the yarn from the package when piecing up. That is to say, the broken end from the package may be drawn off by pulling on the strand, the package rotating freely under the pull so that it is not necessary to turn it by hand as is usually the case.

While the device is herein illustrated in a preferred embodiment it is to be understood that various modifications may be made in the structure and arrangement of its parts without departing from the spirit or scope of the invention. Therefore, without limiting myself in this respect, I claim:

1. In combination with a spindle provided with a conical end bearing, a cop-holder rotatably supported on the spindle, means on the cop-holder cooperating with the conical bearing on the spindle to support the holder concentrically thereof, and a bearing at the opposite end of the cop-holder arranged to take the longitudinal thrust between the spindle and cop-holder in both directions 10 whereby the conical bearing is relieved of all end thrust to eliminate friction at this point.

2. In combination with a spindle provided with a conical end bearing, a cop-holder rotatably supported on the spindle, an adjustable bearing in the cop-holder for cooperating with the conical bearing of the spindle to support the cop-holder concentrically thereof, and a ball-bearing between the spindle and cop-holder adapted to take the longitudinal thrust of the cop-holder in both directions to relieve the conical bearing of all longitudinal thrust whereby it may be adjusted with the proper clearance to eliminate friction at this point. 20

25 3. In combination with a spindle provided with a conical bearing, a rotatable cop-holder comprising a sleeve mounted on the spindle, a threaded opening formed in one end of the sleeve, an annular recess formed in the opposite end of the sleeve, a plug mounted in the threaded opening and adapted to rotate on the conical bearing of the spindle, and a ball-bearing on the spindle disposed within the annular recess of the sleeve for taking the thrust between the spindle and the sleeve in both directions. 35

4. In combination with a spindle provided with a conical tip at its outer end and having its major body portion formed of two diameters with a shoulder therebetween, a rotatable cop-holder comprising a sleeve mounted on the spindle, adjustable means in the end of the sleeve for receiving the tip of the spindle, a ball-bearing at the opposite end of the sleeve abutting the shoulder on the spindle, and a collar carried by the sleeve for engaging the outer portion of the bearing whereby the latter takes both the lateral and longitudinal thrusts between the spindle and the sleeve. 50

5. The combination with a spindle provided with a conical tip at its end and having its major body portion formed of two diameters with a shoulder therebetween, an elongated sleeve having enlarged portions at its ends, a plug adjustably mounted in the outer end of the sleeve and provided with a recess for receiving the tip of the spindle, a ball-bearing on the spindle abutting the shoulder, and a collar mounted on the sleeve engaging the ball-bearing to prevent movement of the sleeve longitudinally of the spindle. 55

6. In combination with a spindle provided with a conical bearing at its end, a cop-holder rotatably supported on the spindle and

comprising a conical bearing adapted to cooperate with the conical bearing on the spindle solely to support the end of the cop-holder, and a ball-bearing located between the spindle and the main portion of the cop-holder to adapt it to support the weight of the cop-holder and cop wound thereon, and also arranged to take the longitudinal thrust of the holder in both directions to relieve the conical bearing of all friction due to end thrust whereby the holder is adapted to rotate at a high rate of speed. 70 75

In testimony whereof I hereunto affix my signature.
